UNITED STATES PATENT OFFICE

LLOYD B. ELLIOTT, OF CHICAGO, ILLINOIS, ASSIGNOR TO ATLAS INDICATOR WORKS, INCORPORATED, OF CHICAGO, ILLINOIS, A CORPORATION OF ILLINOIS

DESIGN FOR AN AMUSEMENT DEVICE

Application filed March 9, 1931. Serial No. 39,006. Term of patent 14 years.

To all whom it may concern:

Be it known that I, LLOYD B. ELLIOTT, a citizen of the United States of America, residing at Chicago, in the county of Cook and State of Illinois, have invented a new, original, and ornamental Design for Amusement Device, of which the following is a specification, reference being had to the accompanying drawing, forming part thereof.

Fig. 2 is an end elevation viewing the device shown in Fig. 1 from the left, and

Fig. 3 is a top or plan view of the device.

I claim:

The ornamental design for an amusement device, as shown.

LLOYD B. ELLIOTT.
